(57) **CLAIM**

The ornamental design for a portable bean roast degree analyzer, as shown and described.

DESCRIPTION

FIG. 1 is an upper perspective view of a portable bean roast degree analyzer showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a first exploded view thereof; and,

FIG. 9 is a second exploded view thereof.

The features presented in broken lines illustrate portions of the portable bean roast degree analyzer that form no part of the claimed design.
